**COMBINED POWDERED MATERIAL
DISPENSER AND STAND**

Marc H. Sessions, Los Angeles, Calif., assignor to United States Borax & Chemical Corporation, Los Angeles, Calif., a corporation of Nevada

Application September 10, 1958, Serial No. 52,601

Term of patent 14 years

(Cl. D4—3)

Fig. 1 is a front view of a combined powdered material dispenser and stand showing my new design;

Fig. 2 is a side view;

Fig. 3 is a top plan view; and

Fig. 4 is a sectional view along the lines 4—4 in Fig. 1.

I claim:

The ornamental design for a combined powdered material dispenser and stand, as shown.
